ELECTRICAL TEST METER

Yoshikazu Kato, 18-3, 1 Tamagawa-cho,
Akishima, Tokyo, Japan

Filed Jan. 17, 1974, Ser. No. 434,111

Claims priority, application Japan July 25, 1973

Term of patent 7 years

Int. CL D10—04

U.S. CL. D10—75

FIG.1

FIG.2

FIG.4

FIG.3

FIG.5

FIG.6

FIG. 1 is a front elevational view of an electrical test meter showing my new design;

FIG. 2 is a top plan view thereof;

FIG. 3 is a rear elevational view thereof;

FIG. 4 is a right side elevational view thereof, the left side being a mirror image thereto;

FIG. 5 is a bottom plan view thereof; and

FIG. 6 is a front perspective view thereof.

I claim:

The ornamental design for an electrical test meter, as shown.
